UNITED STATES PATENT OFFICE.

CYRENUS WHEELER, JR., OF AUBURN, NEW YORK.

HARVESTER.

SPECIFICATION forming part of Letters Patent No. 240,064, dated April 12, 1881.

Application filed October 19, 1880. (No model.)

To all whom it may concern:

Be it known that I, CYRENUS WHEELER, Jr., a citizen of the United States, residing in the city of Auburn, county of Cayuga, and State of New York, have invented certain new and useful Improvements in Harvesters; and I do hereby declare that the following is a full and exact description of said improvements, their construction, and mode of operation, reference being had to the accompanying drawings, making part of the specification, in which—

Figure 1, Sheet 1, is a plan view with that portion of the pole in front of the whiffletree omitted. Fig. 2, Sheet 2, is a side elevation of the same as seen from the right-hand or finger-bar side of the machine. Fig. 3, Sheet 3, is a plan view, showing the gearing, (the cover being removed,) the left-hand drive-wheel, the crank-frame, and gear-frame, the sleeves being broken away to show the shaft and the method of connecting the two frames, also the shifter-fork and its lever. Fig. 4, Sheet 4, is a plan view of a part of the cutter and crank frame, the finger-bar and cutting apparatus, the shoe and intermediate rocking coupling-piece, and the connection of the several parts together for joint operation. Fig. 5, Sheet 5, is a vertical cross-section of the machine in front of the lifting and gaging device and in rear of the pitman or connecting-rod, showing the finger-bar and cutting apparatus raised; and Fig. 6, Sheet 6, is a sectional view across the machine at the same point, showing the finger-bar and cutting apparatus down, with its outer end dropped to its lowest point, the drawings on Sheets 3 and 4 being made on a scale of three inches to the foot, those on Sheets 5 and 6 on a scale of one and a half inch to the foot, and those on Sheets 1 and 2 on a scale of one inch to the foot.

The same letters of reference, where they appear in the several drawings, indicate like parts of the machine.

My improvements relate to that class of machines known to the trade as "double driving-wheeled, front-cut, laterally-projecting, hinged-bar machines;" and the improvements consist, first, in a gear-frame and tongue-socket in one piece, combined with a forwardly-projecting crank and cutter frame hinged thereto on a line concentric with the main axle; second, in

a gear-frame and tongue-socket in one piece, a vibrating cutter and crank frame hinged to said gear-frame concentrically to the main axle and carrying a laterally-projecting cutting apparatus hinged thereto; third, in a gear-frame and tongue-socket in one piece, crank and cutter frame, and a laterally-projecting cutting apparatus united thereto by an intermediate coupling-piece, having hinges or pivots at right angles to each other; fourth, in a gear-frame supporting and shielding the gearing, carrying a driver's seat in rear of the main axle, a rigid tongue, forwardly-projecting cutter-frame, intermediate rocking coupling-piece, laterally-projecting cutting apparatus hinged thereto, and a lever within reach of the driver in his seat for adjusting and holding the rocking piece in its adjusted position; fifth, a gear-frame, driver's seat, rigid tongue, forwardly-projecting cutter-frame, rocking coupling-piece, and laterally-projecting cutting apparatus, with a lifting-lever supported by the pole, and a chain connecting it with the rocking piece; sixth, in two independent driving and supporting wheels, a gear-frame between said wheels, the driver's seat, rigid tongue, forward-projecting vibrating frame, and a draft-link connecting the whiffletrees with the vibrating frame; seventh, hinging the coupling-piece to vibrating frame by an axis parallel to the main axle and hinging the cutting apparatus to the rocking piece in front of the periphery of the right-hand drive-wheel by pivots, the axes of which are arranged below the rocking axis of the coupling-piece; eighth, a lift-lever and locking devices on the pole, a vibrating frame hinged to gear-frame, laterally-projecting cutting apparatus connected to vibrating frame by a shoe and rocking coupling-piece, a three-armed lever pivoted on rear axis of shoe and united by its upper arm to lever on the pole by a chain passing through a sheave fastened to the rocking axis of coupling-piece.

In the drawings, B and B' represent the supporting and driving wheels of the machine. They are located on the opposite ends of the main axle A. This axle supports the gear-frame C by passing through sleeves a' and a², which project from it on either side and serve as bearings, in which the axle A is free to turn.

This gear-frame has formed with it a dish-shaped shell or basin, which surrounds and shields the gearing on its under side and protects it from dirt and the stubble. A second shaft, J, is supported by the gear-frame in rear of the main axle, and parallel to it, by suitable bearings, c, the shaft being fixed therein by a pin, d, the gears E and F being fitted to turn freely thereon. The driving-wheels B B' are provided with pawls pivoted to their internal cases and acted upon by springs, and the main axle A has at each end and inside of the periphery of wheels B B' ratchet-wheels rigidly affixed to it, so that the wheels B B', in their rotation forward, will be locked with the ratchet-wheels on shaft A and impart to it a rotation corresponding to that of the wheels B B', and when the wheels have a backward movement the pawls become disconnected from their ratchet-wheels, and the backward movement of wheels B B' does not revolve shaft A. On shaft A, within the dished portion of the gear-frame, is keyed or otherwise firmly fastened a gear-wheel, D; and on the second shaft, J, is placed a pinion-wheel, E, provided on one end with a clutch-hub, e, its other end having a grooved hub, f, which receives the jaws g of shifter-fork M, which is operated by the pivoted cam-lever N, which has its pivot at h. On the second shaft, J, is also placed a gear-wheel, F, having a corresponding clutch-hub, i, which serves to lock with pinion E when the pinion is moved on shaft J so as to bring it into locking position. Wheels E and F turn freely on shaft J, and when locked together must move in unison as one wheel. The movement of pinion E to and from its locking position with the wheel F is effected by means of the cam-lever N and a spring placed under M, in a chamber provided for it in the gear-frame, acting against a lug on the under side of M to press it and the gear E into locking position with F when not restrained by the cam-lever N. The spring and chamber in the gear-frame are not shown in the drawings.

A pinion, G, and bevel-wheel H, constructed in one piece, are placed on the shaft A and turn freely thereon, the pinion G meshing with gear-wheel F, from which it derives motion, and it, in turn, from the pinion E, with which it locks, and pinion E receives its motion from gear-wheel D, the wheel D receiving motion through the main shaft A from driving-wheels B B' through the ratchets and pawls heretofore described.

Formed in one piece with gear-frame C is a tongue-socket, P, to which the pole A² is bolted, and serves to steady and direct the machine and keep the gear-frame in a plane substantially parallel to the ground over which the machine is moving.

To further protect and shield the gearing a cover, B², is hinged to the gear-frame in front of the main axle by hinges j, so that it can be turned up for oiling, and when down is fastened by locking-button k. On this cover,

supported by the gear-frame and located behind the main axle A, is the seat C² for the driver. This seat has a spring, D², the foot of which is secured to socket-piece l, the seat being secured to its upper end by a rose-piece, m, and hand nut and bolt n. Formed with gear-cover B² is a flange or foot-piece, o, arranged convenient for the left foot of the driver when in his seat. A tool-box, O, is formed in one piece with the gear-frame C and tongue-socket P, and located behind the pole, the rear wall of the tongue-socket serving as the front wall for the tool-box. By locating the tool-box behind the pole and hinging a cover, E², to it a convenient and safe support for the right foot of the driver is provided and the machine rendered more compact and strong.

In order to give to the cutting apparatus the necessary flexibility when united with the machine to follow the surface of the ground closely without being influenced by the position of the gear-frame and pole, a cutter-frame composed of cross-bars R S and brace-bars T U is provided, having a sleeve-piece, Q, for uniting the brace-bars T U to the sleeve a' of the gear-frame C, and on which it is free to vibrate independent of the movements of the gear-frame. These brace-pieces T U extend forward of the cross-bar S, and serve to support the pivot or axis on which the coupling-frame, hereinafter to be described, rocks.

In order to bring the crank-head F², and connecting-rod or pitman G² low down and in advance of the driving-wheels B B', and as nearly in the same horizontal plane with the cutting apparatus as practicable, a crank-frame, L, is provided, having ears H² I² for fastening it to the braces R S of cutter-frame, and an arm, J², having a sleeve, K², for uniting it to the sleeve a² of the gear-frame C, and on which it is free to vibrate or turn independent of the movement of the gear-frame C. The crank-frame L is tubular in form, and is formed with bearings at each end for the crank-shaft K, inserted therein and carried by it. To the rear end of the crank-shaft is fastened the bevel-pinion I, which meshes with the bevel-wheel H on the main shaft A. The front end of crank-shaft K has crank-head F² fastened to it, and carries a wrist-pin, to which pitman G² is connected by a box and swiveling head, its other end being connected to the cutter by spoon-jaws embracing a ball-head, so as to admit of a rocking as well as an oscillating movement of the finger-bar and cutting apparatus without danger of binding or cramping the crank or its intermediate parts connecting it with the cutters.

A coupling-piece, V, is provided, having ears p q, which serve as rocking axis for piece V, which is united to the forward end of brace-bars T U by bolt r nearly parallel to the main axle A. The ears p q are united by a web or flange concave on its upper surface, so as to give room for bolt r, and at the same time pro-

tect and shield it and form a surface on its under side that will pass easily over grass and obstructing objects. Ears *s t* are formed on the piece *V* at nearly right angles to and below the horizontal plane of axis *p q*, so as to bring the rocking-axis of the piece *V* and the parts connected with it far enough above the surface of the ground to admit of its passing easily over loose grass and inequalities and 10 permit the pitman *G²* to work freely under it.

To the ears *s t* the shoe *W* is united by ears *u v* and pivots *w x*, so that the finger-bar *X*, connected with it and projecting laterally or sidewise from the frame-work of the machine 15 and in advance of the driving and supporting wheels, will carry the cutters in a path outside of that in which the machine travels, and will be free to oscillate on the axis *w x* of the shoe *W* and conform to the inequalities of the ground 20 over which it passes, the inner end of the cutting apparatus and the shoe *W* to which it is connected rising and falling with the varying surface of the ground over which it passes, the cutter and crank frame, with the intermediate 25 coupling-piece *V*, to which it is connected, being free to rise and fall with the shoe *W* independent of the driving-wheels, pole, or gear-frame *C*, to which the cutter and crank frame is pivoted.

30 As the cutter and crank frame has its points of attachment to the gear-frame concentric to the main axle *A*, any degree of vibration of the crank or cutter frame will not change the relation of the bevel-pinion *I* to the bevel-wheel *H*.

35 The rear or pinion end of crank-frame *L* projects within gear-frame *C* far enough to bring the pinion *I* within the shell or shield of the gear-frame, the frame at that point having a vertical slot of sufficient depth to permit that 40 end of the crank-frame *L* to rise and fall within the necessary limits.

The cutting apparatus, consisting of the finger-bar *X*, cutters *Y*, and fingers *Z*, is of the ordinary construction now in general use.

45 To the shoe *W* is attached a sole-piece or supplementary shoe, *L²*, which can be removed and replaced at pleasure. To the outer shoe, *N²*, is also attached an adjustable shoe, *Z*.

A shield, *M²*, is provided for the crank-head

50 *F*, and has a brace, *y*, connecting the front end of the shield with crank-frame *L*, to aid in supporting the same against shocks it may receive from stones and obstructions.

The rocking axis of the coupling-piece *V* is 5 located in the rear of and above the plane of the cutters, by which arrangement the rocking of the piece *V* and the shoe and cutting apparatus connected therewith can be much more easily done by the operator than with 10 the axes placed farther forward, as, if placed forward, the weight of the forward end of the crank and cutter frame would be thrown upon the front end of the shoe *W*, and, the ground being the bearing-point, the frame would have 15 to be raised to the same degree the forward end of the shoe rose in rocking it, whereas by

locating it well back and nearly over the rear upward curve of the under surface of the shoe the crank and cutter frame are scarcely influenced in the rocking of the shoe.

To enable the driver to control at all times the angle of the cutters for the better adjustment of the machine to the varying condition of the surface and crop, a lever, *O²*, is provided and fastened by a flange-piece, *a a*, to the 70 rocking piece *V*, its rear end being in convenient proximity to the right hand of the driver in his seat.

A sector-rack, *b b*, is secured to an ear, *c c*, on sleeve-piece *Q* over the main axle *A*, and a 80 locking-bolt, *d d*, controlled by a link, *e e*, and thumb-lever *f f*, serves to lock and hold the lever *O²* and rocking piece *V* in a fixed relative position, or to release and change the same at the pleasure of the driver without stopping 85 his team.

A chain sector-wheel, *P²*, is pivoted on the pole *L* by a pivot-piece, *R²*. To wheel *P²* a lever, *Q²*, is fastened, having a thumb-lever, *g g*, and link *h h*. To the wheel *P²* one end of a 90 chain, *i i*, is fastened. This chain passes under a sheave, *j j*, which is connected to bolt *r* of rocking piece *V*, and its other end is connected to the upper branch of the gag-lever *S²*. This gag-lever is pivoted on the rear pivot-bolt, *w*, of the shoe *W*. This lever *S²* has projecting at right angles from the branch first referred to a branch, *k k*, which has a projection above and below at right angles to it, the lower one, *l l*, serving, by its action on the inner edge of the shoe *W* when brought into action, to raise the outer end of the finger-bar. (See Sheet 5, Fig. 5.) About midway between the point of the shoe and the upper end of lever *S²* another branch, *n n*, projects nearly at 100 right angles to the upright part, and serves as a stop, by striking against the web of rocking piece *V*, to limit the action of the lever *S²* within the required limits desired for the proper elevation of the outer end of the finger-bar and 105 cutters.

A stop, *T²*, is cast with and projects downward from the under side of the pole-socket *P*, and serves as a stop for the cutter-frame when it is raised by its front bar, *S*, striking against it, and thus limits the upward 110 rise of the cutter-frame. In Fig. 5, Sheet 5, is illustrated these several parts with the finger-bar and cutter raised to its full capacity. The driver in his seat, by drawing the upper end of lever *Q²* toward him, by its action through 115 the chain *i i*, lever *S²*, and its connection, first elevates the cutter-frame until it strikes the stop *T²*, and with it the inner end of the finger-bar and shoe, the outer end, especially if in the grass, more than counterbalancing the 120 action of the gag-lever. By continuing the movement of lever *Q²* the driver will bring the finger-bar and cutters to the position shown in Fig. 5, the projection *n n* of lever *S²* resting against the upper side of the web of rocking 125 piece *V*, in which position it can be held by the locking mechanism of the lever *Q²*, con-

sisting of the bolt o locking with the toothed plate p on pivot-piece R^2 .

To restrain and limit the downward movement of the outer end of the cutting apparatus within practical working limits, the projection m on branch k of lever S^2 is provided, and serves, in connection with the web of the rocking piece V , to limit the downward descent of the finger-bar X below a point in which the cutters and their operating mechanism would fail to operate properly. This position of the finger-bar X , gag-lever S^2 , rocking piece V , and lifting-lever Q^2 and its connecting devices is fully shown in Sheet 6, Fig. 6.

The cutting apparatus being connected to the cutter-frame in advance of the driving-wheels, and the cutter-frame, in turn, being connected at its rear end to the axial center of the driving-wheels, about which it is free to vibrate, and as the cutter-frame and the crank-frame must necessarily in its vertical movements be controlled by the cutting apparatus, which must follow the surface of the ground over which it is passing, it will be seen that the weight which the cutting apparatus sustains must necessarily be considerable, and require a considerable expenditure of power to overcome the friction on the ground. To counteract this the whiffletrees U^2 , to which the horses are attached, are pivoted to a sliding piece, q , which is supported on the pole A^2 by a fixed guide-piece, r . The slide q has a flange-piece, s , projecting downward on the right side of the pole, and from this projects a stud, on which the eye of link-rod t is placed, the other end being connected to an eye, u , located on the cutter-frame just back of the rear edge of front brace, S , of cutter-frame. The length of this link-rod t and the location of the slide q on the pole are such as will, when the machine is in operation, reduce the friction of the inner end of the cutting apparatus upon the ground to the lowest point at which it will follow its profile.

For the purpose of convenient transportation from place to place a hook, v , is pivoted to flange-piece a of lever O^2 , and has a coiled spring behind it, (see Fig. 1,) to hold it in locking position, and a link-rod, w , connected by a thumb-lever, x , to rear end of lever O^2 , for releasing the hook by the driver at pleasure.

The finger-bar, when elevated and held in the position shown in Fig. 5, can be turned on its hinge, so that its upper end will incline toward the pole of the machine, in which position the hook v , Figs. 1 and 2, will lock onto the rear edge of the finger-bar X and hold it in that position. When thus elevated the driver in his seat can, by means of the thumb-lever x , release the hook v , and by means of the tracker V^2 lower the finger-bar to the position shown in Fig. 5, and then by means of the lever Q^2 lower the same to the ground. In this position the machine, with the shifter-handle N thrown back and the team attached,

will be ready for operation. The progressive movement of the machine forward over the ground causes a rotation of the driving-wheels B B' and a corresponding rotation of the shaft A , connected with them through ratchets and pawls, and a corresponding rotation in the same direction is given to gear-wheel D . This wheel, gearing with pinion E , gives it a rotation in the reverse direction, and it and gear-wheel F , locked with it, both have the same rotation. F , gearing with the pinion-wheel G , gives it a rotation reversed from that of E and F , but in the same direction as that of D , but with increased speed. The bevel-wheel H being united to G , and both being free to turn on shaft A , do so with less friction than the same wheels mounted on a separate shaft, gaining by the same degree that the shaft A rotates with them in the same direction. The bevel-wheel H , gearing with the pinion I on crank-shaft K , imparts to it and crank-head F^2 increased rotation, and through the connecting-rod or pitman G^2 a reciprocating motion to the cutter Y . The finger-bar and cutting apparatus, being free to rise and fall, follow the profile of the ground both transverse and parallel to the path in which the team travels.

The point of hinging the finger-bar to the coupling-piece V being in line with the tread of right-hand wheel B , a narrow track formed by the tracker serves as a path for both shoe W and wheel B in the succeeding swath, and the shoe being in line with and close to wheel B , follows the ground more perfectly than if differently located.

As the crank-frame is connected with the cutter-frame and rises and falls with it in the up and down motions it receives from the cutting apparatus, it will be seen that the crank-head F^2 must at all times preserve very nearly the same horizontal plane as the shoe W . Consequently the angle of variation between the cutters and the connecting-rod will be less than when the cutter-frame has a movement independent of the crank-frame, and less power will be required to operate the cutter than with a fixed crank-frame.

The axis of rotation of the coupling-piece being in rear of the line of the cutters, the driver can very easily, with the machine in motion, by means of lever O^2 , elevate or depress the point of the fingers Z and cutters Y at pleasure, as the ground or condition of crop may require, and by means of the lever Q^2 raise the whole cutting apparatus to pass stones or obstructions, the action of the team through the link-rod t upon the cutter-frame reducing the weight to be raised to the lowest practical point.

It will be seen that the driver in his seat is so located as to carry his weight in rear of the main axle A , his feet resting on supports U and o , in which position, with the machine at rest, a person of one hundred and sixty pounds weight, with the seat at its central point of adjustment, will balance the pole, neck-yoke, and

whiffletrees. For purposes of adjustment a series of holes (not shown in the drawings) is made in the top part of seat-spring D², for adjusting the seat forward or back, as the weight of the driver may require.

5 The driver's seat being located as described and supported by the gear-frame, the team being attached by a rigid pole to the same, it will be seen that his position is uninfluenced by the vertical movements of the cutter-frame and cutting apparatus, and forward end of the cutter and crank frame in their up and down movements are not influenced injuriously by the gear-frame or the driver supported thereon.

15 The shifting-lever N, for throwing the cutters out of gear, is convenient to the driver, and the gearing protected and shielded from dirt and grit, the whole machine compact, strong, and well balanced, the driver's seat 20 safe and convenient.

Having thus fully described the construction and operation of the machine, what I claim as new, and desire to secure by Letters Patent, is—

25 1. The combination of the gear-frame and tongue-socket in one piece, the forward projecting independently-vibrating crank and cutter frame hinged to said gear-frame concentric to the main axle, substantially as described.

30 2. The combination of the gear-frame and tongue-socket in one piece, the forwardly-projecting independently-vibrating cutter and crank frame hinged to said gear-frame concentric to the main axle, and carrying a laterally-projecting cutting apparatus hinged thereto, substantially as described.

35 3. The combination of the gear-frame and tongue-socket in one piece, the forwardly-projecting independently-vibrating crank and cutter frame, with the laterally-projecting cutting apparatus united thereto by an intermediate coupling-piece, having hinges at right angles to each other, substantially as described and shown.

40 4. The combination of the gear-frame which supports and shields the gearing, the driver's seat supported thereon in rear of the main axle, the rigid tongue, the forwardly-projecting vibrating cutter-frame, the intermediate 45 rocking coupling-piece, the laterally-projecting cutting apparatus hinged to said coupling-

piece, a lever connected with said rocking piece, and within reach of the driver in his seat for rocking it and the cutting apparatus and holding them in their adjusted position, substantially as and for the purposes stated.

5. The combination of the gear-frame, the driver's seat supported thereon in rear of the main axle, the rigid pole, the forwardly-projecting hinged cutter and crank frame, the 60 rocking coupling-piece, laterally-projecting cutting apparatus hinged to said coupling-piece, a lifting-lever supported on the pole of the machine, and the chain connecting the lever with the rocking piece and cutting apparatus, substantially as described and shown.

6. The combination of two independent driving and supporting wheels on the same axle, the supporting and shielding gear-frame between the wheels, the seat for the driver, supported by the gear-frame and located in rear of the main axle, the rigid pole to guide the machine, the forwardly-projecting vibrating crank and cutter frame, the draft-link connected at its rear end to the cutter-frame and at 75 its forward end to the whiffletrees by a sliding head supported on the pole by the fixed guide-piece, substantially as set forth and shown.

7. The rocking coupling-piece hinged to the forward end of the vibrating frame by an axis 80 nearly parallel to the main axle, in combination with the cutting apparatus hinged to the rocking piece by pivots arranged below and at right angles to the axis of the coupling-piece and in front of the periphery of the driving-wheel B, substantially as described.

8. The lifting-lever and locking devices supported on the pole, the vibrating frame hinged to the gear-frame, a laterally-projecting cutting apparatus connected to the frame by a shoe 90 and rocking coupling-piece, the three-armed lever pivoted on the rear axis of the shoe and united by its upper arm or branch by a chain to the lifting-lever on the pole, the whole being arranged and combined for joint operation 95 as shown and described, and for the purposes stated.
